UNITED STATES PATENT OFFICE

THOMAS F. CROCKER, OF CHICAGO, ILLINOIS, ASSIGNOR, BY MESNE ASSIGNMENTS, TO
ASSOCIATED ELECTRIC LABORATORIES, INC., OF CHICAGO, ILLINOIS, A CORPORA-
TION, OF DELAWARE

TELEPHONE SYSTEM

Application filed February 26, 1931. Serial No. 518,429.

This invention relates, in general, to branch exchange telephone systems and more particularly to private automatic branch exchange telephone systems in which local calls are completed by means of subscriber-control 5 automatic switches, and in which incoming calls are intercepted and completed by an attendant. The invention is concerned primarily with the attendant's equipment and with the trunking arrangements for connecting a branch exchange with an exchange 10 of the public telephone system.

Systems of the above type may be arranged with the subscribers' lines accessible via automatic switches controlled by the attendant, or the subscribers' lines may be multiplied to manual jacks at the attendant's switchboard, in which case incoming calls are to be completed directly by means of cord 15 circuits. The present invention contemplates the latter arrangement and one of the main features is the provision of a new and improved cord circuit for completing incoming calls. The cord circuit is arranged so that a branch-exchange subscriber's line can be freed from an incoming connection and made available for other calls without waiting for the attendant to remove the plug of the cord from the line-multiple jack. The 20 cord is further provided with a recall signal, operable under control of the branch-exchange subscriber.

The trunk, which comprises another feature of the invention, is of the same general type as the trunk disclosed in the Lomax 25 Patent No. 1,739,245, of December 10, 1929. The trunk, however, is adapted for connecting a branch exchange with a manual main exchange and is arranged to prevent the accidental release of the branch-exchange 30 switches when an outgoing call over the trunk is answered at the main exchange. This is attained by providing the branch-exchange repeater with a holding circuit which functions until the answering plug has been fully and correctly positioned in the answering jack, whereupon the holding circuit is transferred to the answering end of the trunk.

The various features of the invention, including those specifically referred to and

others, together with the operation of a telephone system embodying the same, will be described in detail hereinafter, reference being had to the accompanying drawings, comprising Figs. 1 and 2. Fig. 1 shows a branch-exchange subscriber's line and switching apparatus and an attendant's cord circuit. Fig. 2 shows a two-way trunk line for connecting a branch exchange with a manual main exchange.

Referring now to Fig. 1, substation A is an ordinary automatic substation whose associated line terminates in a lineswitch LS and is multiplied to a jack J at the attendant's position and to the usual multiple bank 65 contacts accessible to branch-exchange connectors.

Lineswitch LS is of the well-known rotary type, although any suitable non-numerical lineswitch or line finder may be employed if desired. Lineswitch LS, together with other similar lineswitches, has access to local first 70 selectors, such as selector S, shown only in skeleton form. Selector S and similar selectors have access to the usual local trunks terminating in branch-exchange switches (not shown) and in one level, for example, the tenth level, access is had to trunks extending to the main exchange.

Cord circuit C, also shown in Fig. 1 is designed for connecting the interoffice trunks with branch-exchange subscribers' lines. The cord is provided with an answering plug P1 for connecting with the trunk jacks and a calling plug P for connecting with the line-multiple jacks. The usual supervision is provided by the lamps L and L1 and key K provides for connecting up the operator's set and initiating the automatic ringing.

Referring now to Fig. 2, the trunk line T 90 is one of a group of trunks connecting the branch exchange with a manual main exchange. The trunk is accessible in the banks of the branch exchange selectors, such as selector S, and also terminates in jacks at the attendant's switchboard. Jack J2 is used for answering calls and jack J1 is employed for night service, which, in this case, is supplied by connecting the trunk with a particular subscriber's line when the attendant leaves 100

the switchboard. The trunk line terminates the usual line equipment at the manual exchange, although, in this case, one side of the trunk is disconnected from the line relay.

5 The cord circuit at the manual exchange may be of any of the usual types arranged to feed battery and ground to the subscribers.

The operation of the system disclosed is, briefly, as follows: To call another subscriber

10 in the branch exchange, the subscriber at substation A will lift the receiver, whereupon lineswitch LS will operate and select an idle first selector, such as the selector S. The subscriber will then dial the number of the

15 wanted subscriber operating selector S and other branch-exchange switches which will complete the connection in the usual way. Ground is returned by the branch-exchange connector over the release trunk to hold up

20 the lineswitch LS, and this ground, by way of conductor 3, marks the line busy in the banks of the connectors and also at the attendant's switchboard.

A call to the main exchange is made by

25 dialling the exchange digit, which, for convenience, may be assumed to be the digit 0, whereupon selector S is operated to a level in which the trunk lines T are accessible and an idle trunk is selected. The line relay at the

30 manual exchange is operated over one trunk conductor and this relay lights the line lamp of the selected trunk. The manual operator answers by means of the usual cord circuit and further extends the call as required. A

35 holding ground is returned for the lineswitch by the trunk relay group. This holding ground is supplied by a relay in series with the trunk conductor. The relay is energized in a local circuit until such time as the call is

40 answered, whereupon the circuit for the relay is transferred to the battery-feed bridge of the answering cord circuit.

In order to call a branch-exchange subscriber, the main-exchange operator will

45 select an idle trunk line, such as the trunk line T, and insert the calling plug of the cord into the jack J3. The trunk line will be marked busy at the branch exchange immediately upon its being taken into use, but the attendant will not be signalled at this time.

50 When the main-exchange operator desires to signal the attendant, ringing current will be applied to the trunk and the line lamp L2 will light. The attendant will answer the call by inserting the answering plug P1 of the cord circuit, such as C, into the jack J2. Key K will be operated to connect up the attendant's telephone set, and the main-ex-

55 change operator will then advise the attendant as to the particular line wanted. The attendant will test the subscriber's line for its busy or idle condition by touching the tip of the plug P to the sleeve of the line-multiple jack.

60 If the line is busy, the attendant will receive the usual busy click and will inform

the calling operator of this condition. If the line is idle, the attendant will insert the plug P into the line-multiple jack and momentarily operate key K to ringing position.

70 The branch-exchange subscriber will be rung intermittently until the call is answered, whereupon the ringing current will be disconnected and a talking circuit will be completed between the subscriber and the main-

75 exchange operator. In case the branch-exchange subscriber desires to recall the attendant for any reason, the subscriber will actuate his calling device, whereupon the supervisory lamp L flashes to attract the attendant's

80 notice. When the conversation is finished, the branch-exchange subscriber will hang up and the line will immediately be freed

85 from the connection. The plug of the cord C may remain in the multiple jack without busying the line, and therefore, either out-

going or incoming calls may be completed.

Having briefly described the invention, the operation of a system embodying the

same will now be described in detail. It will first be assumed that the subscriber at

90 substation A is calling a main-exchange subscriber. When the receiver is lifted at the substation A, a loop circuit is closed for line

95 relay 5 and the relay operates and completes the testing circuit of the switch. If the

trunk on which the switch wipers are standing is busy, magnet 6 will energize and step the wipers to the next set of contacts. When

an idle trunk is found, for example, the trunk

100 comprising conductors 12-14 terminating in selector S, switching relay 4 will operate

and extend the calling loop through to the line relay of the selector by way of contacts

105 7 and 8. The selector will return a holding

ground over release-trunk conductor 13 in the usual way to hold line switch LS in

operated position after relay 5 restores.

The subscriber then dials the digit assigned

110 for main-office calls, e. g., the digit 0, and

wipers 15-17 of selector S are raised to the

level in which the main-office trunk lines are

accessible. The selector rotates and tests

115 for an idle trunk in the usual way, and when

one is found, switches through and extends

the calling line loop to the trunk repeater.

It will be assumed, for convenience, that the

trunk line selected is the one comprising

120 conductors 18-20, terminating in the trunk

apparatus shown in Fig. 2. The calling loop

is extended over conductors 18 and 20, the

former which may be traced through the

winding of relay 101, trunk conductor 131,

contacts 135, upper winding of line relay 133

to ground. Conductor 20 extends by way

125 of contacts 120 and winding of relay 102 to

battery. Relays 101, 102, and 133 operate

over the above circuit. Relay 133 completes

130 a circuit at contacts 134 for the line lamp L3

at the main exchange, and this lamp glows to

notify the main-exchange operator of the

incoming call. Relay 102 operates and completes a circuit at contacts 114 for relay 103 and at contacts 115, completes a holding circuit for relay 101 so that this relay will be maintained operated independent of the ground through the upper winding of relay 133. Resistance 111 is of such value that relay 133 is not shunted out, but remains operated and relay 101 will also remain operated even though the contacts 135 may be opened. Relay 101 closes an additional circuit for relay 103 at contacts 113. Relay 103 operates, opens the bridge across the trunk which includes relays 105 and 106 at contacts 119, and at contacts 117, applies ground to conductor 19 and the sleeve of the jack J2 to hold up the preceding switches involved in the connection, to mark the trunk busy at the attendant's switchboard, and to operate the visual busy signal 107.

The operator at the main exchange on noting the lighted condition of the lamp L3, inserts the answering plug of a cord circuit into jack J3. Relay 132 operates over the sleeve of the jack and plug, and at contacts 135 disconnects relay 133 from the trunk. The cord, as previously stated, is arranged to supply battery and ground to the calling subscriber and when the plug is inserted in the trunk, a circuit is completed from battery over the tip contacts of the plug and jack, conductor 130, contacts 122 and 116, winding of relay 104 to ground. Relay 104 operates, disconnects relay 102 from conductor 20, and extends this conductor by way of contacts 121 to conductor 130 of the trunk. Relay 104 also applies an additional ground to the release-trunk conductor at contacts 125 and completes a locking circuit for itself at contacts 123. Relay 102 releases, opens the original energizing circuit of relay 103 at contacts 114, and opens the temporary holding circuit for relay 101 at contacts 115. Relay 101 now remains operated in series with the battery-feed relay of the cord circuit connected up at the main exchange. Relay 103 remains energized over the circuit including contacts 113, and relay 104 remains energized in series with resistance 112. The operator may now converse with the calling subscriber and further extend the call in the usual manner by means of the cord circuit.

At the termination of the conversation, the branch-exchange subscriber will restore his receiver, thereby opening the loop over which relay 101 is maintained energized. Relay 101 will restore and open the circuit of relay 103 which will also restore. Relay 103 opens a point in the circuit of relay 104 at contacts 116, removes ground from the release-trunk conductor at contacts 117, and reconnects relays 105 and 106 across the trunk conductors at contacts 119. Relay 104 is slow to release and remains operated when its circuit is opened at contacts 116 by

relay 103. Relay 103, as previously stated, completes the bridge across the trunk line and relay 106 operates in series with the battery feed relay in the cord circuit. Relay 106 is of relatively high resistance and does not permit the battery-feed relay to operate in series therewith so that the operator is given disconnect supervision. Relay 106 completes a new circuit for relay 104 at contacts 128, so that relay 104 remains operated and maintains the busy ground on release-trunk conductor 19 by way of contacts 125. The operator will note the lighted condition of the disconnect supervisory lamp and withdraw the plug of the cord circuit from the jack, whereupon relay 106 deenergizes and opens the circuit of relay 104. Relay 104 then deenergizes and removes the ground from the release-trunk conductor, thereby permitting the preceding switches to release, and the trunk is rendered available for other calls.

A call from the main exchange to the subscriber A at the branch exchange will now be considered. The main-exchange operator will select an idle trunk line, for example, the trunk line T, and will insert the calling plug of a cord circuit into the jack J3. Relay 106, which is bridged across the conductors of the trunk, operates in series with the battery-feed relay of the cord, and at contacts 128, completes a circuit for relay 104 in series with resistance 112. Relay 104, upon operating, prepares the talking circuit by closing contacts 121, prepares a locking circuit for relay 105 at contacts 124, and applies ground to release-trunk conductor 19 at contacts 125 to mark the trunk busy in the banks of the selector switches of the branch exchange. The calling operator now applies ringing current to the trunk and relay 105, whose upper winding is bridged across the trunk conductors in series with condenser 129, is operated. Relay 105 completes a locking circuit for its lower winding at contacts 127, and at contacts 126 disconnects its upper winding from in bridge of the trunk. Lamp L2 is connected in parallel with the lower winding of relay 105 and is lighted from ground by way of contacts 118, 124, and 127. Upon noting the lighted condition of lamp L2, the branch-exchange attendant will insert the answering plug P1 of a cord circuit, such as cord C, into jack J2. Jack spring contacts 108 are closed to complete a circuit from battery by way of resistance 109 for relay 104. Relay 104 was previously energized as described and the latter described circuit merely serves to hold this relay operated when its initial energizing circuit is opened. A circuit may now be traced from battery, winding of relay 30 of the cord, sleeve contact of the plug P1, sleeve of the jack J2 to ground at contacts 125. Relay 30 operates, closes the talking strands of the

cord circuit at contacts 72 and 74, and prepares various holding circuits at contacts 73. Relay 29 is bridged across the talking strands of the cord and operates in series with the battery-feed relay of the calling cord. Relay 101 of the trunk circuit operates in series with relay 29 and the battery feed relay of the calling cord, and at contacts 113 completes a circuit for relay 103. Relay 103 applies an additional ground to the release-trunk conductor at contacts 117, and at contacts 119 opens the bridge including relay 106, which is normally connected across the trunk line. Relay 106 restores and opens the circuit of relay 104 at contacts 128, but this is without effect since relay 104 is now energized in series with resistance 109. The operation of relay 29 of the attendant's cord is without effect at this time. The attendant now actuates key K to the right, thereby bridging her telephone sets across the talking strands of the cord at contacts 64 and 65. A tone circuit is prepared at contacts 62, the busy-test circuit is prepared at contacts 63, and a point in the locking circuit of certain relays is opened at contacts 66. The attendant may now converse with the calling operator and determine the particular branch-exchange line with which connection is desired. Assuming that the call is for the subscriber at substation A, the attendant will test the line for its busy or idle condition by touching the tip of the plug to the sleeve of jack J. If the line is engaged in another connection, there will be a ground on the sleeve of the jack as previously described, whereupon a circuit will be completed from this ground by way of the tip of the plug, contacts 31 and 63, winding of relay 75 to battery. Relay 75 operates and at contacts 76 applies ground to the busy-test winding of the induction coil. The closure of contacts 76 produces the sharp click in the operator's receiver which indicates to her that the line is engaged in another connection. The attendant will then notify the calling operator of the busy condition of the line and the connection will be released as will be described subsequently. Should the attendant disregard the busy indication and plug into the line jack, this would be without effect as relay 22 would be shunted by the ground on the test conductor of the line.

In case the wanted line is idle when the connection is extended as above described, the attendant will not receive the busy click on testing the line and will, therefore, insert the plug P into the multiple jack J. A circuit is thereby completed from ground, contacts 49, winding of relay 22, sleeves of the plug and jack, conductor 3, winding of cut-off relay 4, magnet 6, to battery. Relays 4 and 22 operate in this circuit, the former removing a normal battery and ground con-

nection from the line in the usual manner, and the latter preparing the ringing circuit at contacts 32 and preparing a holding circuit to relay 23 at contacts 33. The attendant now actuates key K to the left, thereby closing a circuit from ground, contacts 60, winding of relay 23 to battery. Relay 23 operates and completes a locking circuit for itself at contacts 35, completes the ringing circuit at contacts 34 and 39, and opens the supervisory circuit at contacts 37. Ringing current is now applied intermittently to the line over a circuit extending from grounded generator GEN, front contacts of the interrupter relay, contacts 34, 40, and 32, tip contacts of the plug and jack, conductor 1, through the bells and condenser of the substation, conductor 2, contacts 21, ring contacts of the jack and plug, contacts 45 and 39, lower winding of relay 24 to battery. The bell at 85 the called substation rings intermittently. Relay 24 is provided with the usual copper slug and sleeve so that it will not respond to the ringing current. When the subscriber answers, a direct-current bridge is closed at the substation and relay 24 operates over the above-described circuit, or, in case the call was answered during a silent period, ground by way of the back contacts of the interrupter relay will be substituted 95 for the grounded generator. Relay 24, on operating, completes a locking circuit for itself at contacts 42, opens the ringing circuit at contacts 40 and 45, and completes the talking circuit at contacts 41 and 44, and at 100 contacts 43 closes an additional circuit for relay 29. The called subscriber's circuit is now extended through the upper and lower windings of relay 27 to battery and ground and relay 27 operates. A circuit is completed for relay 26 at contacts 59 and a tone circuit is completed at contacts 57. Relay 26 operates and prepares a circuit for relay 25 at contacts 52, prepares the supervisory circuit at contacts 54, and connects an additional ground to the circuit of relay 22 at contacts 56.

The attendant will normally restore key K as soon as the automatic ringing of the called subscriber has started. In case the attendant neglects to restore this key to normal she will be given a tone signal as soon as the call is answered. The circuit for applying the tone may be traced from the common tone source, condenser 77, contacts 120 70 and 57, contacts 62 of the key K which is assumed to be in operated position, to the operator's telephone set. The operator will then restore the key to normal and the calling subscriber at the main exchange may 125 converse with the called subscriber at the branch exchange.

Should the subscriber at substation A desire to recall the attendant, for instance to have the call transferred to another line, 130

the subscriber will depress the switchhook momentarily or, preferably, dial the digit one. Relay 27 will restore responsive to the open impulse and complete a circuit by way of contacts 58 and 52 for relay 25. Relay 26 is slow to release and remains operated when its circuit is momentarily opened at contacts 59. Relay 25 operates and completes a locking circuit for itself at contacts 10 46, completes a circuit for supervisory lamp L at contacts 47, and opens the original circuit of relay 29 at contacts 51. Relay 27 remains energized after the impulse is received and maintains the circuit for relay 26. 15 Lamp L now flashes from the interrupted ground by way of interrupter INT. 1, contacts 47 and 54, lamp L to battery. On noting the flashing of the lamp, the attendant will again enter the connection by operating key K to the right. The locking circuit of relay 25 is opened at contacts 66 and the relay restores and opens the circuit of the supervisory lamp at contacts 47. After conversing with the subscriber, the attendant 20 will withdraw the calling plug from the jack J and insert it in the jack of the line to which the call is to be transferred. The procedure followed in completing the new call is exactly the same as that described for 25 completing the call to substation A.

The main exchange operator may also recall the attendant by applying ringing current to the trunk. This current operates relay 28 whose upper winding is bridged 30 across the talking strands of the cord in series with condenser 80. Relay 28 completes a locking circuit for its lower winding at contacts 68, opens its original energizing circuit at contacts 67, and connects lamp 40 L1 to interrupter INT. 1 at contacts 69. Lamp L1 flashes to notify the attendant of the recall.

At the termination of a call such as that above-described, the branch-exchange subscriber will hang up his receiver. The opening of the line loop permits relay 27 to release and complete the previously traced circuit for relay 25. In this case relay 27 remains unoperated and, after a short delay, relay 50 26 releases. Relay 26 completes a circuit for supervisory lamp L1 at contacts 53 and removes ground from the sleeve relay circuit at contacts 56. Sleeve relay 22 of the cord and cut-off relay 4 of the line-switch release, 55 the latter restoring the line to normal condition so that it can be used for other calls. Relay 22 opens the talking strands of the cord at contacts 32 and opens the circuit of relay 23 at contacts 23. Relay 23 restores, opens 60 the ringing circuit at contacts 34 and 39, opens the locking circuit of relay 24 at contacts 36, closes the supervisory circuit at contacts 37, and completes a holding circuit for relay 29 at contacts 38. Relay 24 restores 65 and opens the loop circuit over which relay

29 was held operated during the connection. The latter relay is now energized in a circuit which may be traced from ground, resistance 81, contacts 38 and 50, winding of the relay, tip contact of the plug and jack, contacts 121, trunk conductor 130, ring contacts of the jack and plug at the main exchange, to battery through the battery feed relay of the cord. The battery feed relay does not remain energized in series with relay 81 and on restoring, gives the usual disconnect supervision. In case the operator desires to talk to the branch-exchange attendant, the plug will be left in the jack and relay 29 will remain operated. Lamp L1 will flash as it is connected to interrupter INT. 1 via contacts 70 71, 53 and 47. Lamp L will glow steadily as soon as relays 23 and 26 have restored and will notify the attendant that the branch-exchange subscriber has hung up. 75

In case the main-exchange operator does not desire to recall the branch-exchange attendant, the connection will be pulled down at the main exchange as soon as the disconnect signal is received as above described. The 80 circuit of relay 29 will be opened and the relay in turn will open the circuit of lamp L1 at contacts 71. Lamp L will glow steadily as in the previous case to give the attendant disconnect supervision. 85

The attendant on receiving the disconnect signal will pull down the connection and restore the apparatus to normal condition. It may be noted, however, that the branch-exchange subscriber's line is not prevented from 90 calling or receiving calls in case the attendant delays in pulling down the connection. The ground connections to the sleeve circuit will be removed by the release of relay 26 and the operation of relay 25 as previously described. The calling strands of the cord will be open at contacts 32 and 39 so that relay 27 cannot operate when a loop circuit is again closed at substation A. Further, when a call to or from substation A is established under 100 the above conditions, the ground on the release trunk will prevent relay 22 of the cord circuit from operating in case the attendant should operate key K and release relay 25. The attendant is thus prevented from entering 105 the established connection. 110

What is claimed is:

1. In a link circuit temporarily connected with a line, a signal, means responsive to a momentary interruption of the line for operating said signal in a distinctive manner, and means responsive to a prolonged interruption of the line for operating said signal in a different manner and for freeing the line from the connection with the link. 120

2. In a telephone system, a line terminating in a jack, a cord circuit for extending a connection to said line via said jack, means in the cord for marking the line busy, a signal in the cord operated in a distinctive man- 125

ner responsive to a momentary interruption of the line, and means in the cord for operating said signal in a different manner and for disabling said busy marking means responsive to a prolonged interruption of the line.

3. A telephone system in which connections are extended to called lines by means of a cord circuit and in which the cord circuit is provided with a supervisory signal operated in a distinctive manner under control of the called subscriber, and with means also controlled by the called subscriber for operating the signal in a different manner and for freeing the line from the connection.

4. In a link circuit for connecting a calling line and a called line, means for applying ringing current to the called line, means controlled over the called line for disabling said first means, a supervisory signal, and means controlled over the called line after said first means has been disabled for operating said signal in either of two distinct manners.

5. In a link circuit for connecting a calling line and a called line, means for placing said link in condition to automatically signal the called line, means for changing the link from signalling to talking condition responsive to the called subscriber answering, and a supervisory lamp rendered effective by said last means to flash responsive to a momentary interruption of the called line and to glow steadily responsive to a prolonged interruption of the called line.

6. In a link circuit for connecting calling and called lines, two supervisory lamps, means responsive to a momentary interruption of the called line for causing one of said lamps to glow intermittently, and means responsive to the called subscriber hanging up before the calling subscriber for causing said one lamp to glow steadily and the other of said lamps to glow intermittently.

7. In an operator's link circuit temporarily connected with a line, means for preventing the line from originating or receiving calls, a signal, means controlled over the line for operating said signal in a distinctive manner to recall the operator, and means controlled over the line for operating said signal in a different manner to notify the operator of the termination of the call and for disabling said first means to enable the line to originate or receive calls prior to the disconnection of the link.

8. In an operator's link circuit temporarily connected with a line, means for preventing the line from originating or receiving calls, a signal, means responsive to a momentary interruption of the line for operating said signal in a distinctive manner, and means responsive to a prolonged interruption of the line for operating said signal in a different manner and for disabling said first means to permit the line to originate or receive calls independent of the connected link.

9. In an operator's link circuit temporarily connected with a line, means for preventing the line from calling or being called, a supervisory lamp, means responsive to a momentary interruption of the line for causing said lamp to flash at a predetermined rate, and means responsive to a prolonged interruption of the line for causing said lamp to glow steadily and for disabling said first means to permit the line to call or be called while the link circuit remains connected thereto.

10. In a telephone system, a subscriber's line terminating in a manual jack and in an automatic switch, a cut-off relay for disconnecting the line from said switch, a cord circuit for extending connections to the line via said jack, means responsive to the establishment of a connection for completing an operating circuit for said relay, a signal in said cord circuit, means in the cord controlled over the line for causing said signal to operate intermittently, and means in the cord controlled over the line for causing said signal to operate continuously and for opening the circuit of said relay.

11. In a telephone system, a subscriber's line equipped with a calling device and terminating in a manual jack and an automatic switch, a cord circuit for extending connections to the line via said jack, busying means in the cord circuit for preventing the line from originating or receiving calls while the cord is connected thereto, a signal in the cord, means in the cord responsive to the operation of the calling device of the connected line for causing said signal to operate intermittently, and means in the cord responsive to the subscriber on the connected line hanging up after having answered a call for causing said signal to operate continuously and for disabling said busying means.

12. In a telephone system, a trunk line comprising two conductors connecting a main exchange and a branch exchange, a relay at the main exchange connected to one of said conductors in series with the positive pole of a battery, a relay at the branch exchange connected to the other of said conductors in series with the negative pole of a battery, means responsive to the seizure of the trunk line at the branch exchange for connecting said two conductors to operate both said relays in series, and means responsive to the operation of said second relay for connecting the positive pole of a battery to said one conductor of the trunk to maintain the relay operated independent of said first relay and battery.

13. In a telephone system, a two-conductor trunk line connecting a main exchange and a branch exchange, a relay at the branch exchange, a second relay at the main exchange, an initial series energizing circuit for said relays including a source of current

at the branch exchange, a conductor of the trunk line and ground at the main exchange, and means responsive to the operation of said first relay for connecting ground through a resistance to said trunk conductor at the branch exchange to hold the said first relay operated without deenergizing said second relay.

14. In a telephone system, a two conductor trunk line connecting a main exchange and a branch exchange, a relay at the branch exchange, a second relay at the main exchange, means responsive to a call over the trunk line for completing an initial series operating circuit for said relays including a source of current at the branch exchange, one conductor of the trunk line and ground at the main exchange, and means responsive to the operation of said first relay for closing a parallel local circuit for maintaining the relay operated independent of said second relay while said second relay is maintained operated over said initial circuit.

15. In a telephone system, a main exchange and a branch exchange, a two-conductor trunk line connecting said exchanges and terminating in switch banks at the branch exchange and in a manual jack at the main exchange, a line relay for the trunk line at the main exchange, a call signal controlled by said relay, means for seizing the trunk line at said switch banks to extend a call to the main exchange, means responsive to said seizure for connecting a source of current to only one of the trunk conductors to operate said line relay and said signal, and means responsive to the answering of the call for disabling said relay and said signal, for disconnecting said source of current from said one conductor and for connecting the calling line to the two conductors of said trunk line.

In witness whereof, I hereunto subscribe my name this twentieth day of February, A. D. 1931.

45 THOMAS F. CROCKER.
